UNITED STATES PATENT OFFICE.

MICHAEL MUTRO, OF CHESTER, PENNSYLVANIA, ASSIGNOR OF ONE-TENTH TO JOHN RAWLIUK, OF CHESTER, PENNSYLVANIA.

GRAIN-GRINDING MILL.

1,218,448.

Specification of Letters Patent.

Patented Mar. 6, 1917.

Application filed September 26, 1916. Serial No. 122,245.

To all whom it may concern:

Be it known that I, MICHAEL MUTRO, a subject of the Emperor of Austria-Hungary, residing at Chester, in the county of Delaware and State of Pennsylvania, have invented certain new and useful Improvements in Grain-Grinding Mills, of which the following is a specification.

This invention relates to grain grinding mills.

The object of the invention is in a ready, expeditious and rapid manner primarily to crush or reduce grain, such as corn, to a substantially pulverulent mass and thereafter subject it to a grinding action which will bring it to the desired degree of fineness, the final step of the operation being to separate the coarser from the finer particles of grain, and to segregate these different grades into proper receptacles.

With the above and other objects in view as will appear as the nature of the invention is better understood, the same consists in the novel arrangement and combination of parts of a grain grinding mill as will be hereinafter fully described and claimed.

In the accompanying drawings forming a part of this specification and in which like characters of reference indicate corresponding parts:

Figure 1 is a view in side elevation of the mill.

Fig. 2 is a top plan view thereof.

Fig. 3 is a horizontal sectional view taken on the line 3—3 of Fig. 1.

Fig. 4 is a vertical transverse sectional view of the mill.

Fig. 5 is a longitudinal section through the crushing hopper.

Fig. 6 is a fragmentary detail view of the grinding disks, showing more particularly the mechanism by which adjustments may be effected to vary the fineness of the product.

Fig. 7 is a fragmentary detail view displaying the manner in which the upper grinding disk is driven from the actuating shaft.

Figs. 8 and 9 are elevations, respectively, of the inner and outer sides of the measuring crushing disk.

Figs. 10 and 11 are detail views of certain parts of the apparatus.

The supporting frame of the machine

may be constructed in any suitable manner, and as the particular arrangement of its parts do not enter into the present invention, detailed description thereof is omitted.

The novelty of the invention resides in a peculiar arrangement of disks for initially crushing the grain, and a second series of disks arranged to receive the partially crushed grain and reduce it to the desired fineness.

Arranged in the outer upper portion of the frame is a hopper 1 clearly shown in Figs. 4 and 5 in which is arranged a transverse partition 2 that partially closes the escape from the chute in order to check the too rapid escape of the grain. Beneath the partition 2 are arranged two crushing disks 3 and 4, the former of which is mounted upon a rigid shaft 5, and the latter upon a shaft 6 that is driven through a sprocket chain 7 and sprocket wheels 8 and 9 from the main drive shaft 10. The disks 3 and 4 have their opposed faces serrated or grooved to provide grinding or crushing members, and the said opposed faces are slightly concaved in order to receive a charge of grain. The disk 4 as clearly shown in Fig. 9 is provided on its outer surface with a series of pockets 11, in this instance three, that extend close to the axis of the disk and terminate in discharge openings 12 through which the grain in measured quantities enters the concaved or substantially elliptical chamber between the opposed faces of the two disks 3 and 4. Thus the grain supplied to the hopper 1 will pass down and through the openings 12 between the two disks, and in the event that the charge received is greater than can be accommodated by the openings, the surplus will drop down and be caught by a cover or shield 13 which will retain the grain in position subsequently to be picked up and returned between the disks. In order that there should always be the proper pressure between the two disks, the shaft 6 is provided with a coiled spring 14, one terminal of which bears against a cross-piece 15 on the frame and the other end against a hub or extension 16 formed on the cover 13.

After the grain has been properly crushed, it escapes through the neck 17 of the hopper 1 through an opening 18 formed in a casing 19 inclosing the two grinding

disks 20 and 21, the opposed faces of which are serrated or toothed in the usual manner to secure proper reduction of the grain, and from these disks 20 and 21, the comminuted grain escapes through a chute 22 onto a screen 23 where separation of the grain, according to its fineness is divided and is caught and retained in sacks 24 that are suspended by suitable means from a bar 25 arranged at the side of the mill, doors 26 being provided whereby to control the escape of the grain.

The grain is initially fed into the base or receptacle 27 of a housing 28 in which is arranged an ordinary bucket conveyer 29, the drive chain 30 of which passes around sprocket wheels 31 and 32 carried by shafts journaled in the chute casing, as clearly shown in Fig. 4, motion being imparted to the shaft 32 by a sprocket chain 33 and a series of gears 34, 35, 36, 37 and 38 driven from a pulley 39 mounted upon the main drive shaft 10.

In order that a vibratory motion may be imparted to the screen so that the proper separation or sifting action may be secured, one of the shafts 40 of the train of driving gears referred to carries a crown gear 41 which meshes with a pinion 42, and the latter carries an eccentric 43 that actuates an arm 44 that projects through one wall of the screen frame. Thus as the machine is driven, a sufficient vibratory motion will be imparted to the screen to insure the perfect sorting of the ground product and its discharge into the receptacles provided for it.

As will be obvious, under certain conditions it may be necessary to vary the distance between the disks 20 and 21 in order that the degree to which the grain may be reduced may be varied and to accomplish this result, the shaft 45 carrying the eccentric 43 is adapted to be raised and lowered by adjusting nuts 46 carried by bolts 47 rigid with a fixed part of the frame, the upper end of the shaft 45 being provided with a cleft 48 that is designed to be engaged by a bar 49 carried by the disk 20, the coaction between the cleft and the bar being such that positive rotary motion will be at all times imparted to the disk 20 when the parts of the machine are in operation.

From the foregoing description it will be seen that although the means herein defined are simple in character, that they will be thoroughly efficient for the purposes designed and will co-act in the production of

a highly efficient and effective form of grain grinding mill.

What I claim as new is:

1. A grinding mill embodying a pair of crushing disks, the opposed faces of which are serrated and dished to provide a chamber, the exterior of one of the disks being provided with a plurality of pockets and with openings communicating with the chamber.

2. A grinding mill embodying a pair of crushing disks, the opposed faces of which are serrated and dished to provide a chamber, the exterior of one of the disks being provided with a plurality of pockets and with openings communicating with the chamber, and a shield or cover partially inclosing one of the disks and serving to catch and return grain escaping from the pockets.

3. A grinding mill embodying a pair of crushing disks, the opposed faces of which are serrated and dished to provide a chamber, the exterior of one of the disks being provided with a plurality of pockets and with openings communicating with the chamber, a shield or cover partially inclosing one of the disks and serving to catch and return grain escaping from the pockets, and means for imparting rotary motion to the pocketed disk.

4. A grinding mill embodying a pair of crushing disks, the opposed faces of which are serrated and dished to provide a chamber, the exterior of one of the disks being provided with a plurality of pockets and with openings communicating with the chamber, a shield or cover partially inclosing one of the disks and serving to catch and return grain escaping from the pockets, means for imparting rotary motion to the pocketed disk, and means for permitting the latter disk to yield to excess pressure.

5. In a grain grinding mill, a pair of initial crushing disks, one of which is stationary and the other revoluble and yieldable along its longitudinal axis, the latter disk being provided with pockets communicating with the space between the two disks, and means for collecting and returning to the pockets any grain escaping therefrom on the initial operation of the machine.

In testimony whereof I affix my signature in the presence of two witnesses.

MICHAEL MUTRO.
